UNITED STATES PATENT OFFICE.

JOLLY L. MORRIS, OF CRAFTON, PENNSYLVANIA, ASSIGNOR OF FIFTY-ONE ONE-HUNDREDTHREE TO A. B. COLEMAN, OF PITTSBURGH, PENNSYLVANIA.

DISPENSING APPARATUS.

Application filed March 18, 1924. Serial No. 700,019.

The present invention relates broadly to dispensing and weighing apparatus, and more particularly to an automatically operable mechanism capable of rapidly and accurately filling packages or receptacles with a predetermined quantity or weight of any desired material.

It has heretofore been proposed in the art to which this invention relates to provide automatic weighing or packaging apparatus depending for its operation on the use of electro-magnetic means. Such apparatus has proven quite efficient for accurately measuring materials, but I have found that much more positive action is obtainable by the elimination of the electro-magnetic means and the substitution therefor of impact or positively acting mechanism.

Another object of the present invention is to provide improved cut-off means for the material capable of operation efficiently with different forms of control mechanism whether electro-magnetic or otherwise.

In the accompanying drawings I have shown, for purposes of illustration only, several different embodiments of the present invention, it being understood that the drawings do not define the limits of my invention as changes in the construction and operation disclosed therein may be made without departing from the spirit of my invention or scope of my broader claims.

In the drawings:

Figure 1 is a side elevation, partly broken away, illustrating one embodiment of my invention.

Figure 2 is a top plan view, partly broken away, of the apparatus illustrated in Figure 1.

Figure 3 is a detail plan view, on an enlarged scale, of a portion of the cut-off means.

Figure 4 is a vertical sectional view, on an enlarged scale, through a portion of the cut-off control mechanism.

Figure 5 is a transverse sectional view on the line V—V of Figure 4.

Figure 6 is a perspective view of the trigger and trigger release.

Figure 7 is a detail view of a portion of the trigger illustrating it in cooperative relation to the detent controlled thereby.

Figure 8 is a detail sectional view on the

line VIII—VIII of Figure 1 illustrating the adjusting means for the trigger release.

Figure 9 is a view similar to Figure 1 showing my improved apparatus in cooperative relation to a pair of platform scales,

Figure 10 is a view similar to Figure 1 illustrating a slightly modified embodiment of the invention,

Figure 11 is an inverted plan view of the scale supporting platform,

Figure 12 is a vertical sectional view on the line XII—XII of Figure 10 looking in the direction of the arrows,

Figure 13 is a view similar to Figure 1 illustrating still another embodiment of the invention,

Figure 14 is an enlarged detail view of a modified form of trigger,

Figure 15 is a view similar to Figure 3 taken, however, on the line XV—XV of Figure 13,

Figure 16 is a plan view of one form of attaching mechanism for a pair of so-called even balance scales,

Figure 17 is a side elevation of the construction illustrated in Figure 16,

Figure 18 is a vertical sectional view on the line XVIII—XVIII of Figure 15,

Figure 19 is a detail view of a modified form of nozzle, and

Figure 20 is an inverted plan view of the same.

In carrying out the present invention it is desirable to provide a mechanism adapted to be cooperatively associated with different types of standard scales or weighing devices whereby material in uniform amounts may be rapidly and successively delivered to packages or receptacles without the necessity of any manual control of the actual weighing operation by the operator.

In Figure 1 of the drawings there is illustrated one form of mechanism for accomplishing this result. In this form of the invention there is provided a supporting frame 2 here shown as comprising four tubular corner legs mounted on suitable bases 3 and rigidly connected at their upper ends by a horizontally extending frame 4. Vertically adjustable on the frame 2 is a platform 5 adapted to support a suitable weighing mechanism, such as a pair of so-called even balance scales 6.

Carried by the frame 4 is a hopper 7

adapted to contain the material to be packaged. This hopper has an outlet 8 controlled by a cut-off means illustrated in detail in Figure 3. This cut-off means may 5 comprise shutter sections 9 and 10 adapted to closely engage along the line 11 on substantially the median line of the outlet 8, as clearly shown in Figure 2. The shutter section 9 is provided with a pair of racks 12 and the shutter section 10 with a similar pair of racks 13. One of the racks of each pair is in engagement with a gear 14, the engagement being with substantially diametrically opposite portions of each of the gears 10 whereby rotation of the gears will cause the sections to move uniformly and in opposite directions. These sections are mounted to slide in suitable guides 15 suitably positioned with respect to the outlet 8. With 15 this construction, it will be apparent that with the shutter sections in the position illustrated in Figure 3 the flow of material from the hopper 7 will be prevented, while with the sections in open position, a free 20 flow will be permitted, the rate of flow depending upon the material being handled and upon the extent of opening of the sections.

The sections of the cut-off means are adapted 25 to be manually moved to open position by a bell crank lever 16 pivotally mounted on a pin 17 carried by the frame 2. One end of the bell crank lever is shaped to provide an operating handle, while the opposite 30 end is pivotally connected to a link 18 which is, in turn, pivotally connected to the shutter section 9. Adjustably mounted on the link 18 is a movable stop 20 having an indicating finger 21 adapted to cooperate with suitable 35 graduations 22 on the link. The movable stop may be held in any desired position by a set screw 23. The graduations 22 are so arranged that they indicate the extent 40 of opening of the shutter sections 9 and 10, it being apparent that the graduations thereon may be of any arbitrary character. Positioned so as to engage the movable stop 45 20 is a fixed stop 24. Carried by the pin 17 is a spring 25 arranged to normally turn the bell crank lever 16 in a clockwise direction 50 to move the shutter section 9 to the right, as viewed in Figures 1, 2 and 3, and the shutter section 10 to the left, thereby cutting off the flow through the outlet. Normally, this 55 closing movement of the shutter sections is prevented by a detent 26 adjustably mounted in a slot 27 formed in the projection 28 on the shutter section 10. This detent may also be provided with an indicating finger 60 29 adapted to cooperate with graduations 30 on a projection 28, these graduations preferably being similar to the graduations 22 and arranged in reverse relationship.

Mounted to cooperate with the detent 26 65 is a trigger 31 preferably having a pivotal

mounting 32 in a casting 33 projecting outwardly from one side of the hopper 7. On its under side the trigger 31 carries a roller 34 adapted to cooperate with the detent 26. By referring more particularly to Figure 7 70 of the drawings, it will be seen that this detent has its outer side gradually curved, while its inner side forms an abrupt shoulder. In this figure, the roller 34 is shown in the position it occupies with relation to the detent when the shutter sections are closed. In the drawings, the movable stop 20 and the detent 26 are shown in such position that their respective indicating fingers 75 cooperate with the graduation "3". This 80 corresponds, with the graduations shown, to approximately a half open position of the shutter sections. In operation, with the movable stop and the detent arranged as described, the operator will grasp the handle 85 portion of the bell crank lever 16 and move it in a counter-clockwise direction. This will serve to open the shutter sections to an extent restricted by the engagement of the movable stop 20 with the fixed stop 24. At 90 this time, the curved surface of the detent 26 will have passed under the roller 34 and permitted the roller to drop ahead of the detent, as indicated in dotted lines in Figure 95. Gravity acting upon the trigger 31 will maintain the roller 34 in this position, and thus prevent closing of the shutter sections until the detent is released. It will be understood that with each change of setting of the movable stop 20, the detent 26 will be 100 correspondingly adjusted whereby proper cooperation at all settings is insured between the detent and the trigger.

In operation, the scales 6 are so placed on the platform 5 that a receptacle R on one of the platforms will directly underlie the outlet 8. Upon the accumulation of a predetermined weight of material in this receptacle, the detent is adapted to be automatically released. This may be accomplished 105 by securing to one of the platforms an arm 35 having an adjustable extension 36 carrying a clamp 37. This clamp is adapted to cooperate with a vertically extending rod 38, the upper end of which is shaped to engage 110 the trigger-loop 39 of a balance or scale beam 40. This beam is delicately mounted to move about bearings 41 within the limits of the keeper 42, as well understood in the art. On one end of the beam 40 is a cage 115 43 within which are spaced parallel tracks 44 upon which is adapted to travel a ball 45. In order to protect the tracks 44 from any accumulation of foreign material, and at the same time to permit observation of the ball 120 45, the cage may be provided with transparent means 46.

At the commencement of the filling operation of a receptacle, the beam 40 will be so balanced that it will occupy the position 125 130

illustrated in Figures 1 and 4 with the ball 45 at the extreme right hand end of its cage. This may be accomplished by the provision of an adjustable weight 47 on the beam. The receptacle having been placed in position, and the shutter sections opened by the operator as before described, material will continue to flow into the receptacle until the weight thereof is sufficient to lower the platform carrying the arm 35. Through the action of the rod 38 this movement will be transmitted to the beam 40, causing the same to rock in a counter-clockwise direction whereby sufficient inclination will be imparted to the tracks 44 to permit the ball 45 to roll thereon to the left. At approximately the end of its path of travel, the ball engages a hammer 48 normally urged inwardly by an extremely light spring 49, the spring being substantially of the order of the friction between the hammer and its mounting whereby it insures movement of the hammer into the path of travel of the ball but does not seriously interfere with its movement to dotted line position as indicated in Figure 4. The impact of the ball with the hammer forces the hammer outwardly into its dotted line position in which it engages the upper end of a trigger release 50. This trigger release has a bifurcated lower portion pivotally mounted on the casting 33. The fingers 51 of this bifurcated portion underlie a cross arm 52 formed on the outer end of the trigger 31, as clearly illustrated in Figures 1 and 6. The impact of the hammer 48 with the trigger release causes the same to move in counter-clockwise direction, the pivotal mounting thereof causing the fingers 51 to move upwardly and lift with them the cross arm 52 and the trigger 31. This upward movement of the trigger 31 is sufficient to raise the roller 34 out of holding position with the detent 26, thereby releasing the same and permitting the springs 25 to instantly move the shutter sections to closed position. Upon removal of the filled receptacle from the scales, the arm 38 will be raised upwardly, thereby inclining the tracks 44 in the opposite direction and causing the ball 45 to return to its original position and release the hammer 48. The tracks 44 preferably have a portion 53 arranged at a slightly steeper inclination than the remainder of the tracks. This portion is so located that it will come into action substantially as soon as the ball leaves the hammer 48 to thereby accelerate its return movement. This insures a return movement of the ball such that on the next release operation, the benefit of the full travel of the ball will be obtained. As the movement imparted to the trigger release 50 is comparatively small, it will be apparent that it is desirable to delicately adjust the same, whereby this movement will be effective for rais-

ing the trigger 31 the desired amount. This adjustment may be effected by a screw 54 illustrated in detail in Figure 8, threaded through a bracket 55 carried by the frame 4 and extending over a portion of the trigger release 50 slightly above its pivotal mounting. By screwing this adjustment inwardly, the fingers 51 are brought into a position wherein they slightly elevate the trigger 31, thereby making the release a more delicate one, while, by threading the adjustment screw outwardly, the fingers 51 are lowered, thereby requiring a greater movement of the trigger release to effect release of the trigger.

In Figure 9 of the drawings I have illustrated a slightly different embodiment of my invention, in which, however, figures of reference corresponding to those heretofore used, but having a prime affixed thereto, are used to designate similar parts. In this embodiment of my invention, I have illustrated the mechanism as cooperating with platform scales 6' instead of the even balance scales 6 before described. The scale beam 56 carries a projection 35' cooperating with an adjustable rod 38'. The upper end of this rod passes through a guide 57 into engagement with the outer end of the beam 40'. In other respects the construction of the mechanism is identical with that heretofore described. In operation, when the weight of material in the receptacle is sufficient to raise the scale beam 56, the rod 38' will be raised and the beam 40' inclined in such direction that the ball 45' rolls to the left and actuates the hammer 48'.

In Figure 10 of the drawings there is illustrated a slightly different embodiment of my invention adapted for use with even balance scales of the general character shown in Figure 1. In this figure of the drawings I have designated parts corresponding to parts heretofore described with the same reference characters having, however, 100 added thereto in each instance. In this form of my invention the frame posts 102 are constructed of angle iron and are extended upwardly to directly support the hopper. The horizontal frame 104 is secured at any desired elevation, as indicated. With the form of the invention shown in Figure 1, adjustment of the platform 5 was obtained by individually loosening each of the corner clamps and then raising the platform. With the present form of my invention I have provided means whereby the necessity for clamps is eliminated and the frame may be uniformly raised and lowered. This is accomplished by securing to each of the corner posts, as clearly shown in detail in Figures 11 and 12, a rack bar 60 adapted to be engaged by a pinion 61 on each end of each of the shafts 62. The shafts 62 are intergeared for simultaneous rotation in opposite directions by means of 130

a transverse shaft 63 having adjacent each end thereof a worm 64 meshing with worms 65 on the shafts 62. At one end the shaft 63 may be provided with an operating handle 66. With this construction it will be apparent that as the handle is turned, the platform will be raised or lowered. The pitch of the threads on the worms and worm wheels is such that when the handle is released, the thread will form an efficient lock, thereby effectively holding the platform in its adjusted position. This makes it possible to readily move the platform as desired for filling receptacles of different sizes whereby the fall of material from the hopper is reduced to a minimum.

Instead of utilizing clamping arms 35 for connecting the trigger actuating mechanism to the scales, I may provide a clamp 67, as shown in detail in Figures 16 and 17, carrying an arm 135 with an adjustable extension 136. This extension in turn carries a clamp 137 cooperating with the rod 138 having a pivotal connection with the end of the scale beam 140. In this modification the opposite platform of the scales is adapted to hold the package, the release mechanism being operated upon the upward movement of the rod 138 similar to the operation taking place with the platform scales illustrated in Figure 9.

The forms of my invention heretofore described have been particularly adapted to the handling of bulk material, such as flour, coffee, sugar and the like, adapted to readily flow in their natural condition. By reason of the adjustments provided, the extent of opening of the shutter sections could be varied, thereby causing a larger or smaller flow, depending upon the material being handled and the size of the package or receptacle being filled. In Figures 13, 14, 15 and 18 there is illustrated an apparatus particularly adapted for the handling of fluids. These fluids may be of the character adapted to flow freely under ordinary conditions, or may be of the character adapted to be fed under pressure, as is the case with some of the heavier oils and greases, or fed under either heat alone or heat and pressure, as in the case of lard. For such materials the hopper is entirely eliminated and the material is supplied by a pipe 70 having a manually operable control valve 71 and an automatically operable cut-off means 72. It has been found desirable to utilize the shutter sections for operating the cut-off valve 72, and to permit such an operation the shutter valve sections may be each formed with a recessed end 73. In Figure 15 I have illustrated shutter sections operating exactly in the manner disclosed in Figure 2, but of slightly different construction simplifying and cheapening the manufacture thereof. The recesses 73 are of such size that when

the shutter sections are in closed position, as illustrated in Figure 15, there is sufficient room for the passage of the feed pipe 70. The valve 72 may be of the well known construction comprising an upper sealing member and a lower wedge-shaped seating member having an upstanding bearing 74 thereon permitting substantially universal movement of the seating member. These members are mounted to swing with a shaft 75 into operative position, as illustrated in Figure 18, and into inoperative position within the chamber 76. These movements may be accomplished by providing the shaft 75 with an arm 77 bifurcated at its outer end to straddle the pin 78 projecting upwardly from a rod 79 adjustably mounted in the post 80 secured on the lower side of one of the shutter sections. By reason of this construction, it will be apparent that as the shutter sections are separated, the rod 79 will be moved to the right, as viewed in Figures 15 and 18, thereby turning the shaft 75 in a clockwise direction and moving the cut-off means 72 into inoperative position. This will permit a fluid flow through the pipe 72 until such time as the weight of the receptacle is sufficient to tip the scales and thereby operate the trigger release through one of the mechanisms already described. This will instantly cause the springs controlling the shutter sections to move the same to closed position, thereby turning the shaft 75 in the opposite direction to move the cut-off 72 into operative position. I have found that with certain fluids there is a tendency for drops to accumulate even after the cut-off means has been moved to operative position due to accumulations on the sides of the discharge outlet. This may be effectively overcome with certain materials by providing a removable nozzle 81 having a restricted outlet of the construction illustrated in Figure 18. In other cases I may utilize a nozzle 81', as shown in Figures 19 and 20, having a piece of screen S of suitable mesh placed across its outlet. In order to permit clearing of the discharge nozzle should the same become clogged, I preferably provide a clean-out plug 82 as shown in Figure 13 so located that upon its removal a cleaning rod may be moved freely through the lower end of the pipe 70. It will be understood that if desired a suitable fluid, such as hot water or steam, may be used as a cleaning medium. The construction and operation of the shutter sections in the forms of my apparatus illustrated in Figures 10 and 13, respectively, is the same with the exception that in Figure 10 the shutter sections are not provided with recesses 73 and are not used in conjunction with a supplemental cut-off 72 and its operating connections as required for the handling of fluids.

The present application is a division in part of my application, Serial No. 627,043, filed March 23, 1923.

It will be apparent to those skilled in the art that the construction of the supporting frame may be modified at will by varying the number of supporting standards, or otherwise, to thereby facilitate the use of the apparatus and removal of filled packages therefrom.

In certain cases it may be desired to increase this effectiveness of the rolling ball to secure a greater impact. This may easily be accomplished within the scope of my invention by merely shortening the length of the scale beam 40, 40' or 140, or moving the point of attachment of the rod 38, 38' or 138 slow to its pivotal mounting.

With all of the forms of my invention illustrated herein there is provided a cut-off means which is automatically released upon the accumulation in a receptacle or package of a predetermined amount of material. As soon as the filled package or receptacle has been removed from the scales and a fresh receptacle placed in position the operator may quickly set the apparatus by simply drawing the handle of the controlling bell crank downwardly to open the shutter sections. The extent of opening movement of the sections may be varied and controlled at will, and the sections may be locked in any desired open position by the detent and trigger. This permits uniform quantities of the material to be packaged as rapidly as it is possible for the operator to remove filled packages or receptacles and supply new ones, allowing time only for the actual filling operation.

Other advantages arise from the provision of the second scale beam, whereby the releasing mechanism for the trigger may be itself delicately balanced so as to move easily and effect the desired release of the shutter sections.

Further advantages arise from the provision of a positively acting or impact means for effecting the trigger release.

I claim:

1. A dispensing device for use with weighing scales, including a hopper, a support therefor, a shutter for controlling the discharge from the hopper, manually operable means for opening the shutter, a trigger mechanism for holding the shutter open, means including a pivotal beam for actuating the trigger, and means for transmitting motion from a weighing scale to the beam.

2. The combination in a weighing apparatus, of a pair of scale beams, means cooperating with one of said beams for supporting the package being filled, means for delivering material to said package, means operatively connecting said scale beams for moving the same in unison, and shiftable

means carried by the other beam for cutting off the delivery of said material upon movement of said beams in one direction.

3. The combination with a weighing scale having a scale beam, of a material dispensing means, movable cut-off means therefor, and a second scale beam operatively connected to said weighing scale for controlling the movement of said cut-off means in at least one direction.

4. The combination with a weighing scale having a scale beam, of a material dispensing means, movable cut-off means therefor, and a second scale beam operatively connectively to said weighing scale for controlling the movement of said cut-off means in at least one direction, said scale beam having means for adjusting the balance thereof.

5. The combination with a weighing scale, of a material dispensing means, movable cut-off means therefor, and a rolling weight operatively connected to said weighing scale for initiating the movement of said cut-off means in at least one direction.

6. In a material handling apparatus, a material dispensing means, a cut-off therefor normally urged toward operative position, a trigger for holding said cut-off in inoperative position, a trigger release, a weighing scale receiving material from said dispensing means, and a weight bodily and suddenly shiftable upon movement of said scale for operating said trigger release.

7. In a material handling apparatus, a dispensing means, a cut-off comprising oppositely movable shutter sections, means normally urging said sections to closed position, an adjustable trigger mechanism for holding both of said sections in open position, and release means including a pivotally mounted beam for releasing the trigger mechanism irrespective of the adjustment thereof.

8. In a material handling apparatus, a dispensing means, a cut-off comprising oppositely movable shutter sections, means normally urging said sections to closed position, means for holding said sections in open position, and impact operated release means for said holding means.

9. In combination with a complete weighing scale including a weight indicator, a portable supply hopper, and scale operated means including a scale beam separated from the weighing scale to interrupt the discharge from said hopper.

10. In combination with a weighing scale, a portable supply hopper, means to adjust said scale for a predetermined amount of discharge from said hopper, and scale operated means including a scale beam separated from the weighing scale to then interrupt said discharge.

11. In combination with a weighing scale, a portable supply hopper, a movable control shutter therefor, means for adjustably limit-

ing the opening movement of the shutter, and scale operated means for controlling the closing movement of the shutter.

12. In combination with a weighing scale, 5 a portable supply hopper, means to adjust said scale for a predetermined amount of discharge from said hopper, means to regulate the discharge opening thereof, and scale operated means to interrupt said discharge upon reaching said predetermined amount.

13. In combination with a weighing scale, a portable supply hopper; scale operated means to interrupt the discharge from said hopper and manually operable self-locking 15 means to regulate the height of said hopper above said scale.

14. In combination with a weighing scale, a portable supply hopper, a shutter for the discharge opening thereof, manually operable adjustable means for opening the shutter, means to maintain said shutter in the selected open position, spring actuated means to move said shutter into closed position and scale operated means to release said shutter.

25 15. In combination with a weighing scale, a portable supply hopper; a shutter for the discharge opening thereof, said shutter being composed of two abutting sections oppositely 30 slideable in a common plane, manually operable means to separate said sections, means to maintain said shutter sections separated, spring actuated means to move said sections into abutting or closed position, and scale operated means to release said shutter.

35 16. In combination with a weighing scale, a portable supply hopper, a shutter for the discharge opening thereof, said shutter being composed of two abutting sections, means to simultaneously and equally slide said sections in opposite directions in a common plane, manually operable means to separate

said sections, means to maintain said shutter sections separated, spring actuated means to move said sections into closed position, and scale operated means to release said shutter. 45

17. In combination with a weighing scale, a portable supply hopper, a shutter for the discharge opening thereof, said shutter being composed of two abutting sections, means to simultaneously and equally slide said sections in opposite directions in a common plane, manually operable means to separate said sections, means to select the amount of separation of said sections, means to maintain said shutter sections separated in the 50 selected position, spring actuated means to move said sections into closed position, and scale operated means to release said shutter.

18. In combination with a weighing scale, a portable supply hopper, a shutter for the 55 discharge opening thereof, said shutter being composed of a plurality of cooperating sections oppositely movable, manually operable means to separate said sections, self locking means to maintain said sections separated, means to move said sections into closed position upon release thereof, and scale operated means to release said sections.

19. In combination with a weighing scale, a portable supply hopper, a shutter for the 60 discharge opening thereof, said shutter being composed of two cooperating sections, means to simultaneously slide said sections in opposite directions, means to separate said sections, means to maintain said sections separated, means to move said sections to closed 65 position when released, and scale operated means to release said sections.

In testimony whereof I have hereunto set my hand.

JOLLY L. MORRIS.
